UNITED STATES PATENT OFFICE.

WILBUR H. APPLETON, OF SPOKANE, WASHINGTON, ASSIGNOR TO WESTERN METALS COMPANY, OF SPOKANE, WASHINGTON, A CORPORATION OF WASHINGTON.

METHOD FOR CENTRIFUGAL AMALGAMATION AND PRECIPITATION OF GOLD AND SILVER.

Application filed April 28, 1919, Serial No. 293,302. Renewed December 17, 1923.

To all whom it may concern:

Be it known that I, WILBUR H. APPLETON, a citizen of the United States, residing at Spokane, in the county of Spokane and

5 State of Washington, have invented new and useful Improvements in Methods for Centrifugal Amalgamation and Precipitation of Gold and Silver, of which the following is a specification.

10 This invention relates to an improved method and means for the centrifugal amalgamation of the nobler metals by mercury.

One of the most important features and 15 utilities relates to the conversion, electrolytically, of dissolved values from a solution to a suspension in liquid, the particles of such suspension being discharged onto the mercury, and acted upon by centrifugal 20 force to drive the values, in suspension, into the mercury by which the values are amalgamated.

As an electro-centrifugal amalgamator, it 25 is a special feature of my invention to connect the anode of the circuit with the pulp solution, forming the electrolyte, the cathode of the circuit being connected with the mercury, and as the bowl rotates, imparting revolvable movement to the mercury there- 30 in, the latter having its cathodal surface infinitely multiplied and thereby very greatly increasing the rate of precipitation with respect to the mercurial area presented.

A further very important feature consists 35 in the simultaneous amalgamation of both the free or uncoated values present in the pulp, by the sole medium of centrifugal action, and the dissolved values converted electrolytically from solution into suspen- 40 sion, which latter are acted upon to drive them into the mercury not only by the centrifugal force to which they are subjected, but also by the cations which radiate through the electrolyte toward and seek the 45 mercurial cathode.

It is a feature of my invention to centrifugally spread the mercury over its supporting surface in the bowl not only in uniform thickness but in such a manner as to 50 retain the mercury in the form of a united body. Thus it is a great desideratum of my invention to prevent the mercury from flouring. It is also a feature of this invention to spread the mercury in as thin a body

as possible, over its supporting surface, as it 55 is well known that merely a covering of the surface is sufficient for the purposes of amalgamation and anything further is mere waste. In order to promote the greatest efficiency and speed of amalgamation, it is 60 a feature of my invention to prepare the pulp solution sufficiently liquid, and to feed it in such proportion in volume, with relation to the mercurial area, as to prevent the particles in suspension from banking on the 65 mercury and also to cause the heavier pulp particles, comprising the values, to film over the mercurial surface as thinly as possible and thereby bring the values in suspension into the closest possible proximity to the 70 mercury as the solution flows upwardly along the surface of the latter.

To the end that all the foregoing may be accomplished, it is a feature of my invention to provide the rotating bowl with a 75 mercury supporting surface which curves upwardly and radially outwardly from near the axis of rotation to the discharge edge, and which surface is continuously smooth and unbroken so that the mercury is free 80 to assume the position to which it may be impelled by centrifugal force. Thus it is a very important feature of my invention to absolutely and entirely free the mercury from any obstruction or impediment which 85 might either retard its freedom of movement or destroy its integrity as a united body. With this in view, it is a feature of my invention to gradually increase the diameter of the supporting surface toward the 90 discharging edge whereby the mercury may be readily controlled and sustained wholly by the rate of rotation imparted to the bowl, and further; the curvature of the bowl, the quantity of mercury employed, 95 together with the speed of rotation, are all so correlated, especially in the sense of mutual reciprocation, that the joint action will result in maintaining gravity and centrifugal force in an equilibrium of balance 100 whereby not only the mercury, which does not and will not discharge over the edge of the bowl, but also the heavier pulp particles on the mercury, will both be spread not only thinly by centrifugal action, but 105 with a thinness which is uniform throughout the height of the surface. This correlation of the forces is such that the speed im-

parted to the bowl will not raise the mercury therein to the discharge edge but will raise the solution to and over the discharge edge, only the particles of higher specific gravity being amalgamated.

Other features and objects of my improved mechanism and method will be more fully described in connection with the accompanying drawing and will be more particularly pointed out in and by the appended claims.

In the drawing:—

Figure 1 is a vertical sectional view of the device of my invention.

15 Figure 2 is a diagrammatic view illustrative of my theory of the reason why my improved rotary mercurial cathode has a multiplying cathodal surface.

Figure 3, is a view similar to Figure 1, 20 showing the device as it would appear in actual continuous operation with the heavier particles of the pulp thinly filmed over the mercury and illustrating how the liquid portion of the pulp takes a parabolic curve 25 different from that of the mercury.

Like characters of reference designate similar parts throughout the different figures of the drawing.

A bowl is indicated at 1 and the same is 30 provided with a mercury supporting surface 2, the latter, at least, being of an electrically non-conducting material, the surface being a non-amalgamating and non-amalgamated surface. I have used a wood 35 bowl having its surface coated with an asphaltum base. A mounting 3 is provided on which the bowl rests and an axially disposed pipe 4 has an inlet end 5 opening to the bowl through the bottom thereof, the 40 pipe extending through the mounting 3. Any suitable form of thrust-bearing 6 may be provided, the same being mounted upon a frame 7. The pipe 4, which also functions as a shaft, is journalled in a second bearing 8 mounted on a lower portion 9 of the frame. The lower open end of the shaft 4 will be suitably provided with a valve 45 controlled outlet (not shown) and a pulley 10 will be driven by a belt or other suitable means. A spillway has an inner wall 12 50 which is shown overhanging or overlapped by a flange 13 depending from the edge of the bowl. The spill-way is stationary and the outer and inner walls 11 and 12 will be connected by a bottom wall 14 which is inclined downwardly for delivery to a common outlet 15. A hopper 16 delivers to a discharge pipe 17 which depends into the bowl into contact with the electrolyte. An 55 anode or plus wire 18, of a circuit, is diagrammatically indicated as being connected with pipe 17, while a cathode or minus wire 19, of said circuit, is diagrammatically indicated in connection with pipe 4. As the 60 mercury 24 extends downwardly in the me-

tallic pipe 4 it will be seen by reference to Figure 3 how the circuit is closed through the mercury from minus wire 19.

Next referring to the novel form of mercury supporting surface 2, it will be seen 70 that from line 20 to line 21, which latter is appreciably the limit of upward travel of the mercury 24, that the surface is continuously smooth and unbroken, line 20 being practically the inward limit of the active 75 area because of its proximity to the neutral zone or axis of rotation. Thus the surface 2 extends upwardly on a curved line, the bowl having an increasing diameter from 20 to 21 the slope being of a precipitous declivity. However, the formation of this surface 2 is calculated and developed not necessarily for the production of the precise curve shown, but for the purpose of presenting such a slope to the mercury 24 that 80 with a given quantity of the latter and given speed of rotation of the bowl, the mercury 24 will traverse and annularly ascend this slope in such a manner as to be spread over the area thereof in substantially uniform 85 thickness, as shown in Figure 3. The very precipitous incline will resist in a cumulative manner the ascent of the mercury 24 under centrifugal action and this will serve to unite rather than segregate or divide the 90 mercury so that as the latter spreads over the surface it will remain united without either the bowl, or the forces acting upon the mercury having any tendency to disintegrate the latter, but on the contrary, promoting unity of the mercury. This will 95 prevent flouring. As will be seen, the mercury supporting surface is parabolic in form.

The shape of the bowl is designed so that 105 the action of centrifugal force sending the mercury upwardly, will be balanced by the action of gravity tending to cause the mercury to descend. Now it is an important feature of my invention to correlate these 110 forces with the shape of the bowl and the speed of rotation with a view of spreading the mercury evenly over the surface 2. In large operations it is a matter of economy, and an important one, to use as little mercury 115 as possible in order to get efficient action and so long as the surface is covered, nothing is gained by having a two-inch thickness of mercury at the bottom of the bowl and an eighth of an inch near the top of the bowl. In order to demonstrate the 120 fact that the forces of gravity and centrifugal force are in balance, I have disposed balls of different weight, as indicated at 22 and 23, at different annular elevations on the inner surface 2 and these balls neither seek to ascend or descend, when the bowl is empty. However, fill the bowl or put enough water in to ascend to the balls and 125 they will immediately descend. I have also 130

measured the depth of the mercury 24 at different elevations to prove that the thickness is uniform.

An important feature of the foregoing resides in the fact that wholly by the speed of rotation, the mercury 24 can be prevented from ascending beyond a given elevation whereas the liquid portion of the pulp, while it very slowly traverses its ascent up the mercurial surface, will flow over the edge and carry away the lighter particles. Furthermore, and this is very important, with this design of bowl the heavier particles of pulp not only thinly but uniformly film over the mercury 24 and by reason of this fact the values are the more readily driven into the mercury 24 because of their near proximity thereto. This is important not only as regards speed of operation but also efficiency.

In straight amalgamation, where the ore is not dissolved in solution, the current is sent through the mercury to prevent the latter from fouling and sickening, which I do not claim as new. All of the foregoing description relates not only to the importance of the features with respect to straight amalgamation wholly by centrifugal action, but also applies to electrical precipitation and centrifugal amalgamation, the latter of which features I will next describe in detail.

The pulp is ground to the desired fineness in a suitable solution which dissolves some of the metals and frees the surfaces of the remainder of the metals so that the nobler of the latter can be centrifugally driven into the mercury by straight amalgamation independent of any electrolytic action. However, as regards the metals which are dissolved, it is necessary to convert these into suspension prior to amalgamation, and it is one of the novel features of this invention to precipitate these dissolved metals by electrolysis, in the centrifugal apparatus, so that electrical precipitation and centrifugal amalgamation may be simultaneously carried out. It is not necessary to recite either the ingredients of the pulp solution or the electrolyte, as far as this invention is concerned.

In actual practice of the invention, a bowl of the form shown in Fig. 3 with a diameter of 16 90/100 inches and depth of 5 96/100 inches has been used, the diameter being measured at the point 21 and the depth being measured from this diameter to the point 20.

With this type of bowl rotating at a constant speed of eighty-three revolutions per minute, forty pounds of mercury will spread over the surface 2 in a uniform thickness, as shown in Figure 3. Of course in practice, the axial outlet is closed at a higher elevation than that shown, as regards the mer-

cury, in pipe 4. As the bowl gradually attains its maximum speed, the mercury will ascend toward line 21 and will not seek to pass above said definite limit upwardly nor will it descend below said limit when the bowl is rotated at a constant speed, as stated. Of course I do not speak of constant speed as the final ultimate in accuracy, as a variation of one to three revolutions per minute is not perceptible to the naked eye as regards its effect upon the mercury although doubtless such variation would actually cause some alteration in the position of the mercury. Thus any mechanical device or prime mover imparting a practically constant speed to the bowl will be sufficient. When the stated speed has been reached, as near as I can determine, all friction between the mercury and the bowl ceases and becomes nil and the mercury rotates bodily at the same speed as the bowl.

The bowl is first set in motion not only to spread but to maintain the mercury 24 evenly distributed over the face of the bowl, as hereinbefore described. The electrolyte 27 and the pulp in solution having been introduced or discharged onto the mercury 24 and the circuit having been connected up, the operation will be as follows: Care will be taken only to admit as much as will cause the heavier pulp particles 25 to thinly film over the mercury 24, as it is the object to not only thinly coat the amalgamating surface with pulp particles but to evenly distribute the pulp particles over the mercurial surface. The result of this is to bring, in a thorough and systematic manner, every heavier particle of the pulp constituents into contact with the mercury 24 and to coat the latter with pulp particles 25 continuously and without interruption. All of those constituents of the pulp except the nobler metals will be gradually carried over the discharge edge 26 of the bowl by centrifugal action, and the solution 27, as the conveying medium, the intake being regulated to not exceed or fall below the rate of discharge thereby preventing the particles in suspension from banking on the mercury 24.

The dissolved metals will be converted by electrolysis into solids and thereby freed for action by centrifugal force to be driven into the mercury 24. The rapidity with which amalgamation can be carried out by my improved method and apparatus has been amply proven in actual practice. To the best of my knowledge and belief, among the reasons why a relatively small amount of mercury 24 in constant revolution will perform the service of many times the quantity of mercury 24 or mercurial surface in a state of quiescence, is that because the cathodal surface in my improved invention is infinitely multiplied by reason of its rotation, the actions continuously taking new lines of

radiation to the cathode, as shown diagrammatically in Fig. 2. In this figure the unbroken radial line may be theoretically considered as the first cation radiating toward the cathode. The broken lines may be considered the constantly renewing cations which are at all times seeking the cathode because of its infinitely multiplied surface.

Furthermore, when centrifugal force and gravity are in a state of balance, and the mercury 24 does not ascend or descend while revolving, it is my theory that the metal particles in suspension in the mercury 24 meet less resistance in their descent, in the bowl 15 within the mercury 24 than would be the case if these minute particles were interfered with by variably flowing currents of mercury 24, which latter condition would certainly result, if centrifugal force and gravity were 20 not in a state of balance.

By reason of the supporting surface being continuously smooth, and also because it is not only a non-amalgamated but also a non-amalgamating surface, the mercury 24 is at 25 all points of area exposed to uniform friction and therefore I have found that there is no slippage between the mercury 24 and the bowl surface, and that this is one of the most 30 important reasons why the mercury 24 does not flour.

Because the mercury 24 is held together, as a united body by the very powerful and sustained action of centrifugal force, the pulp does not scour the mercury 24, with consequent loss thereof notwithstanding the fact that rotation of the mercury body and the pulp is not in actual synchronism and that there is relative movement of the two, during joint rotation thereof.

It is also my theory that after the dissolved metals have been transformed into suspension in the electrolyte and before reaching the mercury, their amalgamation is materially assisted, electrolytically by reason of the cations moving toward and seeking the cathode.

As a method, my invention consists in electrolytically converting metals in solution, into suspension, and applying not only centrifugal action but also the cations for driving the values in suspension into the mercury 24, and in this connection, my invention, as a method, includes setting the mercury 24 in motion on an incline to the horizontal, and in supporting the mercurial body in correlation with the application of balanced forces to spread the mercury 24 in a united body.

It is a feature of my improved method, to cause the mercury 24 to act as the cathode, and to set the mercury 24 in, and maintain it in motion to multiply the cathodal surface not only to increase the rate of precipitation but also to greatly reduce the amount of mercury necessary.

According to my invention, after the

mercury 24 has reached its final operative position in the bowl, the mercury revolves in absolute synchronism with the bowl and there is no relative movement between the two.

I do not wish to be limited to this specific disclosure of my invention, either in apparatus or method, except for such limitations as the claims may import.

I claim:—

1. The herein-described method of preventing flouting of mercury for amalgamating purposes, which consists, in setting a body of mercury in motion at an upward inclination to the horizontal, and in supporting the body of mercury in correlation with application thereto of opposing forces to maintain the mercury united and spread the same in uniform thickness.

2. The herein-described method of centrifugally amalgamating the nobler metals with mercury, which consists, in rotating a mercury supporting surface of such upward slope from near the axis of rotation to the discharge edge that centrifugal action will spread the mercury over such surface, and in feeding pulp onto the mercury in such quantity relation with respect to the speed of rotation and the area of the mercury that the heavier pulp particles will relatively thinly and uniformly film over the mercurial surface.

3. The herein-described method of centrifugal amalgamation of the nobler metals, which consists, in revolving an upwardly inclined non-amalgamating and non-amalgamated mercury supporting surface whereby friction to free movement of the mercury is uniform to prevent flouting, in coordinating the speed of rotation of said surface in such relation to its inclination as to balance the action of gravity and centrifugal force, whereby the mercury will rotate in substantially fixed relation with said surface without ascent or descent or relative rotation therein, whereby the values in amalgamation in the mercury will be free to descend therein without resistance of variant currents of flow of the mercury.

4. The herein-described method of preventing flouting of mercury in centrifugal amalgamation of ore, which consists, in rotating a body of mercury on and with a parabolic supporting surface presenting a cumulative resistance to ascent of the mercury thereon to prevent flouting, and in speeding up rotation of said surface in such relation to the curvature and size of said surface that the mercury will remain a united body and will uniformly and thinly film over said surface and will remain substantially quiescent with respect thereto without ascending or descending thereon.

In testimony, that I claim the foregoing as my own, I hereby affix my signature.

WILBUR H. APPLETON.
